UNITED STATES PATENT OFFICE.

WALTER B. BLISS, OF LOS ANGELES, CALIFORNIA.

DESIGN FOR A PUZZLE-BADGE.

40,914.

Specification for Design. Patented Sept. 27, 1910.

Application filed April 9, 1908. Serial No. 426,131. Term of patent $3\frac{1}{2}$ years.

To all whom it may concern:

Be it known that I, WALTER BANCROFT BLISS, a citizen of the United States, residing at Los Angeles, in the county of Los Angeles and State of California, have invented a new, original, and ornamental Design for a Puzzle-Badge, of which the following is a specification, reference being had to the accompanying drawing, forming a part thereof.

The figure is a plan view of a puzzle badge showing my design.

As shown, my design is intended for use as a puzzle and also as a badge representing a possible and an impossible voyage of battle-ships from the Atlantic to the Pacific. The contour of the continents is raised above

the plane of the base, leaving a free passage between it and the edge of the base. Two parallel semicircular ridges with their concave faces toward the continents, are formed upon the left of said continents; the nearest one connecting with the continents at the upper end and having a passage therebetween at its lower end, and the farther one having a free passage around both ends and between it and the edge of the base.

I claim:

The ornamental design for a puzzle badge, as shown and described.

WALTER B. BLISS.

In presence of—

JAMES R. TOWNSEND,
M. BEULAH TOWNSEND.
